PICTURE TRANSMITTER

Kurt Schlesinger and Gerhard Liebmann, Berlin, Germany; said Schlesinger, assignor, by mesne assignments, to Loewe Radio, Inc., a corporation of New York

Application January 23, 1937, Serial No. 122,032
In Germany January 29, 1936

2 Claims. (Cl. 178—7.1)

There has become known for the transmission of television images the ikonoscope, which performs a chronological storage of the photo-electric charges, and is, therefore, already more sensitive to the extent of 3 to 4 orders of magnitude than the classic television transmission device comprising the Nipkow disc and photo-cell. It has been found in practice, however, that the sensitivity of a good ikonoscope is still insufficient for the transmission of daylight scenes under normal conditions of illumination, and it is necessary to secure the aid of very powerful artificial light sources. In the case of weak light sources the practicability of the use of an ikonoscope is limited by the noise of the amplifying tubes themselves.

On the other hand a new amplifying method has become known by the researches of Zworykin and others, the "electron multiplier method," which is distinguished by a considerably smaller natural noise, as in this method any feed current is missing. If it were possible to combine this method of direct current amplification with the principle of the chronological storage of the ikonoscope, an apparatus would thus be obtained, the operation of which would be in turn to the extent of one order of magnitude more sensitive than that of the normal ikonoscope associated with a conventional amplifier. A combination of this kind of the two apparatus known per se is impossible in their known form. The known ikonoscope is a voltage generator, i. e., upon the scanning of the picture receiving area it supplies potential oscillations to a free terminal, and accordingly can only be employed in conjunction with the grid of a normal amplifying tube but is not suited to an electron current amplifier. For a device to be so suited it is necessary to act not as a voltage generator but as an electron current generator.

The following invention by Kurt Schlesinger and Gerhard Liebmann relates to corresponding modifications of the ikonoscope in which, in contradistinction to the known ikonoscope, electrons are liberated upon the scanning of an accumulating light-electric surface, and in which these electrons are drawn directly on to an anticathode, at which there occurs a current amplification as known from the "multiplier," due to a powerful secondary emission. The currents thus amplified may then be passed further to an additional anticathode and may thus be additionally amplified in the manner already known. The complete operation takes place in the tube ac-

cording to the invention in a common high vacuum.

Various forms of embodiment of the invention will hereinafter be described by way of example, reference being to be made to the accompanying drawings, of which—

Figs. 1 and 2 are diagrammatic sectional elevations of electron tubes according to the invention together with a diagrammatic partial showing of the optical and electrical equipment thereof, whereas

Fig. 3 is a plan view of a detail of the tube shown in Fig. 2, and

Fig. 4 is a diagrammatic elevation of a modification of this detail and its circuits.

Further modifications of a tube such as shown in Fig. 1 are illustrated by further showings of this same type in Figs. 5, 6 and 7.

Fig. 8 is a plan view of a special mosaic structure according to the invention, of which structure Figs. 9 and 10 show a part on an enlarged scale substantially in plan view (9) and in sectional elevation (10).

Figs. 11 and 12, again, are showings of a similar type as Figs. 1 and 2 and illustrate certain modifications and improvements according to the invention.

Fig. 13 is a plan view of a mosaic structure for use in a tube as shown in Fig. 12.

In Fig. 1 is illustrated a form of embodiment of the idea according to the invention, in conjunction with which the essential explanations may be given. In the original ikonoscope the image receiving area itself consists of insulated photo-electric particles. These particles lose electrons during the storage period and have the same compensated for by the scanning electron ray. In this device, therefore, no new electrons are to be gained during the scanning, but electrons are consumed from the ray. In the arrangements according to the invention these operations, therefore, are modified accordingly.

The storage plate must recover electrons during the period of rest, and these must be liberated point-by-point upon the scanning operation. For this purpose it is proposed first electro-optically to produce on a mosaic surface an electron image of the image-receiving area. In Fig.

1 the image-receiving area 1 is a coherent, i. e., undivided photo-electric plate. On to this plate is projected through the objective 2 by way of a small mirror 4 an image of the object 3. Of

this light-optical image 3' an electron image is projected on to a plate 7 by means of a simple 55

electrical lens comprising the electrodes 5 and 6. This plate 7 in turn consists of an insulating sheet of mica 8, which is furnished on the side directed towards the interior of the tube with a layer 7a divided in mosaic fashion and comprising minute photo-cells, and on the opposite side with a coherent counter-electrode 7b. The latter is earthed. The primary electrons, represented by the rays 9, are caused to traverse magnetic field 10, which is to be imagined at right angles to the paper. They are then deflected in the manner shown. By means of an electrode 5a, which may be raised to about the same potential as 5, the electrons 9 are slowed before impinging on the mosaic and reach the mosaic with a potential of less than 100 volts. At this low speed they are no longer capable of liberating secondary electrons from the layer 7a, but merely charge negatively to different potentials the particles of this layer. The layer 7a is illuminated from an optical scanning line screen 11 by way of a lens 12 and thereby discharged point by point. There then result per image element electron currents of varying intensity, corresponding to the number of electrons 9 which have successively reached the image element in question during the storage period. Since these electrons leave the plate, i. e., have an opposite direction of movement to the primary electrons 9, they will be circularly deflected in the opposite sense by the magnetic field 10. The path is represented by 13. The electrons are liberated from the layer by an anode 14. They then meet against a first anticathode 15 in the manner known from the "electron multiplier" and liberate there a multiple secondary electrons, the paths of which are designated 16 and which now impinge on a new anticathode 17, and so forth. Each additional stage of this nature is furnished with a new, appertaining suction anode, the suction anode in respect of the paths 16 being designated 18. The potentials of these successive anodes consecutively increase by the same amount respectively in relation to one another. Each accelerating anode is connected with the appertaining plate, i. e., the anode 14 with the anticathode 15, the anode 18 with the anticathode 17, etc. The final anticathode, in this case 17, is connected by way of a coupling resistance 19 with the final accelerating potential 20, so that to this resistance there may be connected an end amplifier 22.

In Fig. 1 a magnetic field has been employed for spatially separating the primary and secondary currents. As already known, there may also be employed in place thereof an electrostatic electron-optical system. Further, in place of a straight-view primary reproducing electron-optical system 5, 6, 5a with a built-in optical deflecting mirror 4, a reproduction may be made use of with magnetically or electrically curved rays, wherein such deflecting mirrors may be dispensed with. Further, the screen area 11 consisting of luminous points may be produced by a mechanical decomposing machine in conjunction with a technical light source or by the luminous screen of a Braun tube.

All of these different forms of embodiment, to which others may also be added, have in common the feature of the invention consisting in the fact that of the image original 3' there is first projected an electron image on to a storing mosaic surface, that the storing mosaic is then discharged point by point by light, and that the

stored electron currents thus liberated are amplified by secondary emission by way of direct current amplification to above the noise level of tube amplifiers by which the electric excitations are dealt with afterwards.

A tube for converting a light image into an electron image has already been described in a practical form of embodiment in the application Ser. No. 111,815. The described operation of the point-by-point discharge of the stored charges of the photo-cells occurs only in the manner described if there is no appreciable secondary emission from these cells in the dark condition. As a rule, i. e., with electron rays having speeds of between 100 and 2,000 volts, this requirement is not complied with, but the cells are charged to the approximate potential of the incoming ray and remain at this potential independently of the intensity of the ray impinging thereon. According to a feature of the invention, therefore, either the primary ray must be slowed, so that the electrons meet against the layer at a speed of less than 100 volts. This may be performed by the cylinder electron lens as described, or for instance by coating the wall of the tube 6 with a conductive layer, e. g., in the form of a graphite spiral and applying the desired terminating potentials to the ends of this spiral (after retardation). The desired effect may also be accomplished by the use of rays of more than about 2,000 volts, since from a certain speed upwards the secondary emission no longer suffices to cover the current balance between incoming and leaving electrons and a point-by-point charging then occurs in proportion to the intensity of the primary current.

A particularly simple embodiment of the optically scanned ikonoscope in conjunction with a current amplifier is shown in Fig. 2. Herein 23 is a plate having perforations of image-point size, and 24 is a two-dimensional structure which is situated opposite thereto and consists, so to speak, only of image points, and in which points of silver are arranged on an insulating supporting plate 25. An arrangement of this kind has already been described in a previous application Ser. No. 111,815. Both the perforated plate 23 as well as the point plate 24 are activated with caesium and made photo-sensitive only on the side facing each other. The light from the object 3 to be transmitted passes by way of a reproducing lens 2 through the spaces between the image points 24 onto the activated layer side of the perforated plate 23. From the latter there are liberated photo-electrons, which, by reason of their low natural speed, impinge on to the oppositely disposed image points 24 and charge these negatively to an extent which depends on their number. Should the initial energy not be sufficient, there may be applied between the perforated plate and the anode, by the introduction of a very fine-mesh anode 26, a small bias of approximately 10 volts, which accelerates the electrons in both directions.

Fig. 3 is a magnified front view of a portion of the perforated plate, showing that a wire net 26 may further be introduced in such fashion between the apertures in the perforated plate 23 that the wires thereof are finer than the connecting pieces between the apertures of 23, so that when looking from the left in Fig. 2 merely the connecting pieces of the perforated plate 23 and when looking from the right merely the image points of 24 are visible, whilst the anode 75

net 26 does not produce any interfering shadow effect.

Another solution to the electron-acceleration problem is shown in Fig. 4 and manages without an intermediate anode 26. For this purpose a high-frequency circuit with at least twice the maximum produced picture frequency is connected between the perforated plate 23 and an auxiliary electrode 27 and is operated by a high-frequency generator at 28. The electrostatic field then provides for the liberation of the electrons from the perforated plate. The same high-frequency generator may also release electrons from the mosaic plate 24 in the opposite direction by way of a push-pull circuit, as illustrated in Fig. 4. For this purpose a counter-electrode 27a is required.

The mosaic plate 24, having thus been charged negatively point by point during the storage period, is then illuminated in a successive manner by a scanning ray of light proceeding from the right hand through a lens 12. As scanning light source there is again employed a mechanical system of the Nipkow disc type or a Braun tube—generally speaking a surface 11 over which there moves a luminous image point. In this way the electrons which have accumulated at the mosaic 24 are photo-electrically liberated, conveyed outwards towards the perforated plate by means of a fine-mesh net 30' with a positive bias 29, acting as anode, and then concentrated on to an anticathode 15 by means of an electron-optical system, which in its simple form comprises two cylinders 30, 31, of which 31 is raised to a still higher positive bias 21. At 15 secondary electrons are liberated in the manner known per se and are concentrated by a further and smaller electron-optical system 33/34 upon a final anode 17. The electron-optical system shown is an electrostatic one. A battery 20 is applied with its full voltage of approximately 200 volts relatively to 15 to the cylinder 34 and the intercepting plate 17 by way of the coupling resistance 19, whilst a medium potential of 20 is adjusted at the reproducing electrode 33, thus effecting focusing. 22 is the input tube of the associated image amplifier.

The double-plate arrangement 23/24 contains at least as many image points as indicated by the square of the desired number of lines. The arrangement is preferably produced mechanically, by first stamping a perforated plate 23. With a size of approximately 20 cm. square, and 400 lines, an individual aperture in this plate still has a diameter of -5 mm., which may be readily produced. If there is employed the precision art of producing finest apertures of approximately 50μ in diameter as developed in the production of Nipkow discs, a 400-line screen 60 may even be produced in a plate of 4 cm. square.

In Fig. 5 is shown an arrangement similar to that of Fig. 1. A deviation in direction is assumed amounting to 45°. The object 3 to be televised is reproduced by a lens 2 on the primary cathode 1. The cathode 1 is a coherent photo-electric layer. The image 3' is reproduced by the lens 50—52, the sharpness of which is adjusted at 51, on the mosaic 7a. A magnet field 10 perpendicular to the plane of the paper deflects all of 70 the reproducing rays 9a to 9c at the point of their maximum construction by the same angle (45° have been shown), and accordingly acts as an electron reflector. The reproduction remains sharp in the plane 7a. A slowing system formed 75 of three rings 53 in conjunction with the resist-

ance 57 slows the electrons down to about 0 volts. In this way secondary emission is avoided, and there results on 7a a charge image having charges which are the more negative the brighter the corresponding points of the image on 1 happen to be. A lens 12 reproduces a luminous scanning area, for example the surface of a television cathode ray tube, 11, on 7a. Since 7a is photo-activated, the illuminated points discharge electrons until they have entirely lost 10 their negative charges. The thus produced cathode rays 13a to 13c are deflected by the same magnetic field 10 in the opposite direction and enter into a tubular member 30, being accordingly completely separated from the primary 15 currents.

Following on the positive tubular member 30 there may be employed any of the known multiplication systems for a direct amplification of electronic currents. There is shown in the drawing an embodiment with an electrostatic multiplier. As well known, such a multiplier consists of a tubular member 30 and a tubular member 31 which is positive in relation to 30. The anti-cathode 15 is met at the point 59 by the primary 20 rays 13, and the electrons 60 liberated in excess at that point under certain known conditions are concentrated by the tubular member 34, and finally collected by the anode 17.

A further embodiment of the idea of the invention is set forth in Fig. 6. The image to be transmitted is reproduced on the photo-cathode 1 by means of the lens 2. In the example shown the photo-cathode is represented as being perpendicular to the axis of the tube and the direction of the light falling thereon, and must accordingly be assumed to be transparent. It may, however, also be inclined to the axis of the tube (with correspondingly modified arrangement of the lens 2) in Fig. 7. It is possible to impart 35 to the photo-cathode, in the manner known per se, a curvature as shown, which eliminates the reproduction fault of the electron-optical reproducing system 61', 61'', . . . 50, 62, which reproduces on the net electrode 63 the electrons 45 liberated from the photo-cathode. The electron-optical reproducing system, in the manner known per se, may consist of a system of rings 61', 61'', etc., a diaphragm 50 and an anode cylinder 62. By adjusting the bias of the diaphragm 50 the 50 scale of enlargement of the system may be varied within certain limits. The potentiometer which serves to impart to the said electrodes the potentials necessary for obtaining a good reproduction is not shown in the drawings. The electron-optical reproduction, in the manner known per se, can also be performed by magnetic means or by a combination of electrostatic and magnetic means. The electrode 63 represents a mosaic composed of electrically conductive metallic pellets 60 embedded in a highly insulated fashion in a conductive net. The production of this electrode will be described later. It separates the aforesaid electron-optical reproducing system mechanically and electrically from the scanning system 64. The side of the mosaic electrode facing the photo-cathode 1 is preferably furnished with a coating due to which the metallic pellets insulated one against the other, assume the property that the number of secondary electrons 65 liberated per oncoming primary electron is considerably smaller than 1. It has been found that certain carbon modifications, for example finely divided soot, are very well suited for this purpose, 70 as the ratio between the number of liberated 75

secondary electrons and the number of primary electrons amounts to about 0.5 in the case of practically all potentials concerned. This layer of soot must naturally be applied so thinly that no conductive bridges are formed between the insulated metallic pellets. Instead of applying the mentioned coating of a substance giving off a poor supply of secondary electrons the total accelerating potential of the electron-optical reproducing system 61', 61'', etc., may be so chosen that the yield factor of secondary electrons remains below 1.

Under the stated conditions each of the insulated metallic pellets is charged to a potential which is somewhat more negative than the potential of the supporting conductive net, which is the same as that of the final electrode of the reproducing system 61', 61'', etc., and the same as that of the final anode of the scanning system 64, which is still to be described. The potential up to which the metallic pellets are charged is proportional to the light intensity values of the light that impinges on the corresponding points of the primary cathode. By the embedding of the insulated metallic pellets in a conductive net the individual pellets are to a high degree screened off electrically one against the other; in addition the capacity is considerably greater than in the case of the known mosaic screens deposited on mica, which reduces the danger of self-discharge, the potential of each element remaining comparatively low.

The side of the mosaic screen 63 facing away from the photo-cathode 1, or in other words the rear sides of the negatively charged metallic pellets, are scanned in the example shown by means of a cathode ray, in the manner known per se. For producing the cathode ray there is employed the electrode system 64, and for performing the scanning the deflecting system 65, which may be an electrostatic, a magnetic or a mixed electrostatic-magnetic deflecting system. To avoid distortions of the image the axis of the cathode ray system 64 is disposed vertically to the mosaic screen 63. If the photo-cathode 1 is inclined in relation to the axis of the tube the axis of the scanning system is preferably inclined in such fashion that the resulting scanned image is again undistorted.

The accelerating potential of the cathode ray scanning system is so chosen that each electron of the scanning ray liberates more than one secondary electron. This effect may be further improved upon by sensitizing the metallic pellets on the side facing the cathode ray, for example by means of caesium. In this case the accelerating potential may be adjusted to 2,000 volts. This potential, however, as all potentials given in the drawings, are merely quoted by way of example.

Owing to the fact that each electron of the scanning ray liberates more than one secondary electron, so long as the metallic pellets of the mosaic 63 are negative in relation to the conductive net, or in relation to an equilibrium potential of a value near that of the net potential and dependent on the conditions of operation of the tube, all metallic pellets will be discharged to this equilibrium potential when the scanning ray passes thereover. A higher positive charge than corresponds to the equilibrium potential cannot take place, since, as well known, the higher potentials thus resulting would reduce the yield factor of the secondary electrons to a value below 1.

The secondary electron current impulses released upon the scanning by the cathode ray and

the discharging of the pellets to the equilibrium potential correspond in their strengths to the charges of the scanned metallic pellets, and accordingly to the light intensities of the image elements of the image projected on to the photo-cathode 1. These secondary electronic impulses are now amplified in a current multiplier of the known kind, applied somewhat obliquely to the main tube, and are conducted by way of the terminal anode 17 and the resistance 19 to the final amplifying tube 22. As current multiplying means there may be employed any of the known arrangements, for example those with magnetic or electrostatic deflection of the secondary currents supplied by different plates, or those with a superimposed auxiliary oscillation of ultra-high frequency, which hurls the electrons repeatedly against suitable secondary electron cathodes. The most suitable for the present embodiment of the invention, however, is the use of a multiplier which consists of a series of grids 66', 66'', etc., suitable for supplying secondary electrons, which are provided with increasing potentials. In an electron multiplier of this kind, nearly the entire amplification of the image impulses which may be necessary may be performed.

Instead of scanning the mosaic with an electron ray it is, also in this arrangement, possible to perform the scanning by means of a ray of light, which compensates the negative charges of the metallic pellets by the liberation of photo-electrons.

Instead of the electrons which are liberated upon the scanning there may also be multiplied, in accordance with the invention, those electrons by means of which the photo-cathode, on to which the image of the object to be transmitted is projected, is reproduced on the mosaic electrode. An arrangement of this kind is shown in Fig. 7, which at the same time illustrates the aforementioned modification in the position of the photo-cathode in such fashion that the light meets against the same at an angle and the photo-electrons leave the same on the side on which the light impinges. The use of an inclined front-view photo-cathode has the advantage that the primary sensitivity is considerably higher than in the case of the transparent-view cathodes as employed up to now.

In Fig. 7, 1 is the photo-cathode, which is inclined at an angle of 45°, and on to which the image of the scene to be transmitted is projected by means of the lens 16. The electrons which are liberated at the photo-cathode 1 in correspondence with the light intensity of the individual points of the image, and constituting the current I_p , are projected by the electron-optical reproducing system 67', 67'', etc., on to the metallic plate 68, which is likewise inclined at an angle of 45°.

The reproducing system consists in the manner known per se of rings 67', 67'', 67''', 67 to which, by means of a potentiometer (not shown) there are imparted suitable potentials which increase in the direction from the cathode to the metallic plate 68. In this arrangement the first ring 67' may be adapted in its form to the inclined position of the photo-cathode 1, and in accordance with the invention may consist of a thin-wire metallic fabric in order not appreciably to weaken the image light possibly projected through the same. The final reproducing electrode 67 of the said system is preferably maintained at the same potential as the metallic plate 68 and the first ring of the electron-optical re-

producing system 69', 69'', ... This potential in relation to the photo-cathode 1 is so chosen that on the one hand there is still obtained a good sharpness of reproduction and on the other hand a high secondary emission factor. The metallic plate 68 is sensitized, preferably by silvering, oxidation and the application by vaporization of caesium, in which manner an increased yield of secondary electrons is obtained. The 5 most favourable potential is then situated between 500 and 1,000 volts, for example at 800 volts. The primary electrons accelerated by this potential each liberate a multiple number of 10 secondary electrons. These form the current I_s , 15 and produce the image on the mosaic screen 63 owing to the electron-optical system consisting of the rings, 69', 69'', 69''', 69. The total difference in potential which is maintained between the secondary cathode 68 and the last ring 69, 20 and accordingly approximately (with the exception of the fluctuations caused by the generated impulses) also the coherent conductor (metallic net) of the electrode 63, corresponds in turn to the most favourable compromise between as good 25 as available a reproduction and the liberation of secondary electrons, and may again amount, for example, to 800 volts. Owing to the fact that the secondary current I_s now liberates tertiary electrons at the mosaic screen 63, the individual 30 mosaic elements are charged to a considerable positive potential in relation to the coherent conductor of the mosaic electrode 63. The tertiary electrons are picked up by the final ring of the reproducing system 69', 69'', ... 69. The 35 charges of the mosaic elements correspond to the light intensity of the individual corresponding points of the photo-cathode 1, and accordingly of the original image. By the scanning of the mosaic 63 by the cathode ray 1A, which may 40 be caused by the deflecting coils 65, the charges of the mosaic 63 are compensated in the manner known per se, and image impulses are accordingly generated, which flow from the coherent conductor by way of the resistance 19 to 45 earth and accordingly control the grid of the input tube 22 of the subsequent amplifier. The mosaic screen 63 is so inclined in relation to the scanning electron ray that the image distortion is compensated which is caused by the inclined 50 position of the photo-cathode 1.

It is naturally also possible in the arrangement according to Fig. 7 to repeat the described liberation of secondary electrons. The possible number of reproductions, however, is limited, 55 as with each additional electron-optical reproduction the lack of sharpness of the reproduction increases, the more so as secondary electronic currents always contain a considerable proportion of comparatively rapid electrons, 60 which results in faults in reproduction corresponding to the chromatic errors of light-optical systems.

The image transmission tube set out in Fig. 6 is free from these disadvantages, as only the 65 primary photo-electrons, which have a very low starting speed, are once reproduced electron-optically. The multiplication by secondary electron liberation does not take place before, by means of an electron ray or a ray of light, electron 70 impulses have been produced, the strength of which corresponds to the local light intensity of the image. The multiplying device then no longer requires to have point by point reproducing properties.

75 An essential component part of the present

invention is represented by the embodiment of the two-sided mosaic employed. Two-sided mosaics have already been proposed previously, which consist of an arrangement of small aluminium bars coated electrolytically with aluminium oxide.

It has been found, however, that this kind of mosaics or "multiple grids" can only be employed in tubes with thermionic cathodes, above all, therefore, for image receiving tubes, as the 10 percentage of gas owing to these mosaics is too large to permit of the introduction of such mosaics into vessels containing highly sensitive photo-cathodes. This gas cannot be sufficiently expelled even by a several days' preliminary 15 treatment in vacuum at high temperatures.

According to a further feature of the invention, therefore, the mosaic consists of a metallic—preferably tungsten—net, which is coated with aluminium oxide. Silver pellets are fused into 20 the meshes thus insulated.

For producing a mosaic of this kind the procedure is preferably as follows: Preliminarily burnt, ground, pure aluminium oxide, which is mixed with collodion and amyl acetate, is sprayed 25 on to the tungsten net from both sides by a spray gun, which requires to have a very fine nozzle, so that, while the meshes are not yet closed, all wires are well imbedded. After drying the net is annealed in a hydrogen furnace at approximately 1,800° C. In this way the aluminium oxide is sintered to form a firmly adhering, highly insulating coating on the wires of the net. Following thereon the pores are filled out with powdered silver, or a certain amount of silver amalgam is painted into the meshes and the mercury expelled by heating. The net is then heated in vacuum to a temperature above the melting point of the silver. Owing to the surface tension the silver forms into small pellets, 30 so that there is one silver pellet in each mesh. This operation is repeated until the pellets have assumed such a size that they completely fill out 35 the pores.

Fig. 8 shows the finished mosaic 63 fitted into the tube. The net is stretched over small metal plates 70 and insulating plates 71, which after the production may be metallized. They are held together by the rivets 72. In this manner the mosaic fills out the entire cross-section of the 40 tube and separates the discharge spaces. Fig. 9 shows a piece of the mosaic, Fig. 10 a sectional elevation of this piece. In these figures 73 are the individual tungsten wires of the net, 74 is the surrounding insulating aluminium oxide coating, and 75 are the fused in silver pellets. 76 are particles of soot, which are applied to the one side in order to suppress there the emission of secondary electrons, and 77 are coatings which are applied to the opposite side and favour the 45 emission of secondary and photo-electrons.

It is naturally possible to replace the tungsten, for example, by molybdenum, to employ in place of aluminium oxide another, preferably ceramic 50 insulating material, such as magnesium oxide, and in place of silver to fuse in another metal, such as zinc or copper.

A mosaic of the kind described may naturally 55 also be employed in image transmission and receiving tubes of other kinds in which a two-sided mosaic is desired.

In the production of a transmission tube according to Fig. 6, in which the side of the mosaic 63 facing the photo-cathode 1 is coated with 75

carbon, it is desirable, pending termination of the sensitization of the photo-cathode 1, to close the opening in the electrode 50 by means of a piece of mica, which is subsequently removed, in 5 the same manner as the intermediate spaces between the other electrodes of the reproducing system 61', 61'', . . . 62, the absorption by the carbon of the vaporized caesium being so strong that otherwise the sensitization of the photo-cathode 1 could only be performed with difficulty.

Certain improvements and simplifications in respect of transmission tubes as described in the foregoing will now be set forth. The improvements relate in the first place to the electron 15 multiplier fitted into the transmission tube. There is employed a multiplier consisting of a number of nets prepared for a good emission of secondary electrons. According to a further feature of the invention, there is provided between 20 every two consecutive nets a metallic ring disposed edgewise, the internal diameter of which preferably corresponds to the largest diameter of the secondary cathode nets. This ring, is maintained, preferably by means of a regulable potentiometer, at the potential of that next adjacent net cathode which, in the particular system concerned, assumes the function of the cathode, or at a somewhat more negative potential. By means of the "potential pot" thus 25 formed there occurs a concentration and directing of the liberated secondary electrons towards the next secondary cathode, which in this system acts as the anode. This concentration is of importance in view of the space charge effective 30 in the higher stages and also on account of the numerous secondary electrons with high lateral speeds which are present in every stage. Between the mosaic plate and the first secondary cathode net of the multiplier there may also be 35 provided in accordance with the invention a "concentration ring," which preferably consists of a comparatively large-mesh, extremely thin-wire metallic fabric (both in the case of light ray as well as electronic ray scanning). It is 40 apparent that this measure of intermediate concentration is also important quite generally in 45 electron multiplying systems.

An additional improvement consists in the fact 50 that the axis of the multiplying system coincides with the axis of the electron-optical system causing the reproduction of the photo-cathode on the mosaic plate. In this way favourable conditions are provided in respect of the sucking off of the 55 electrons liberated at the mosaic plate and entering the multiplier. The bundle of cathode rays or light rays necessary for liberating these electrons falls on to the mosaic plate in an inclined direction, and the spacing between the first net of the multiplier and the mosaic electrode is so 60 large that there is no interference with the scanning bundle of cathode or light rays. When using a scanning ray of light the portion between the mosaic plate and the first secondary cathode 65 may be furnished with a semi-conductive transparent coating, which connects the mosaic electrode with the first secondary cathode. In this way a more even suction field is ensured at the mosaic electrode. The axes of the reproducing 70 bundle of light and the scanning bundle of cathode or light rays again form such an angle that the resulting image distortions compensate each other.

A simplification, which is independent of the 75 aforesaid improvements, which are capable of be-

ing employed separately, consists in the fact that there is not employed an electron-optical reproducing system for reproducing the photo-cathode on the mosaic plate, but that a conductive net is provided just in front of the mosaic electrode, and is photo-electrically sensitized on the side facing away from the mosaic screen. The weak field caused by the discharge of the mosaic points upon the scanning operation extends through the meshes of this net and sucks the 10 liberated photo-electrons on to the storage electrode.

An exemplary embodiment of the stated improvements and simplifications is set forth in Fig. 11. Herein 78 is the mosaic electrode, 79 the 15 photo-cathode net situated closely in front of the same, 66, 80, 17 the multiplying system, and 64 the scanning cathode ray system. The scanning movement of the cathode ray is produced by the coils 65. The electron-multiplying system consists of the nets 66, 66', 66'', . . . disposed one behind the other with intermediately disposed concentration rings 80, 80', 80'' . . . and the pick-up electrode 17. The potential provided by a potential source 81 is applied in a suitable manner to the multiplier stages by means of the potentiometer 82. The current impulses developed are conducted to the end amplifying tube 22 by way of the grid resistance 19. The reproduction on the photo-cathode 79 of the image 3 to be 30 transmitted is produced by the lens system 2. The light ray and cathode ray axes are preferably inclined at an angle of 45° in relation to the mosaic screen, in the manner shown.

A further embodiment of the invention is ill- 35 istrated in Fig. 12. Herein, 8 is the mica plate of an ikonoscope, 7a the mosaic which in the known manner is illuminated from the object 3 through the optical device 2 and is scanned by means of the cathode ray system 64. According 40 to this embodiment of the invention there is provided on the rear side of the mica sheet 8, not a coherent collector plate as heretofore, but a second mosaic 7c. To this mosaic there is applied in close contact with its surface a coherent grid 45 83 which consists of a fine network 83. Behind this first net 83 there follow a plurality of other nets 66, 66' etc. By means of a terminal anode 17, which may also be a wall coating of the tube, the 50 amplified electron current is picked up, to be converted at the resistance 19 into fluctuations in potential which excite the amplifier 22. The rear mosaic 7c is illuminated by a constant light source 84, possibly with a condensing lens 85. The grids 66, 66'—17 are given increasing positive potentials in a manner such as known from the "multiplier" designed by Weiss.

The operation of this arrangement is as follows: By the illumination of the primary mosaic 60 7a by the image there is produced in the known manner an electrical charge image, which contains positive residual charges at the illuminated points and no residual charges at the unlighted points. Upon the scanning by the cathode ray 65 65 the positive residual charges are neutralised. This results in a negative potential impulse at that one of the capacitatively coupled points of the rear mosaic 7c which is situated immediately opposite the point just scanned.

By the illumination of the rear mosaic by the light source 84 all particles of the mosaic were 70 previously charged positively owing to their photo-electric emission until their potential had become equal to the potential of the net 83. The 75

contents of the meshes and the wires thereof accordingly had the same potential. If now by reason of the said scanning of 7a the said negative potential impulse is developed in the content of any of the meshes, the content of the particular mesh is able to emit electrons, the surroundings 83 being positively biased in respect of this part of the mosaic. These electrons might be directly collected and amplified in the circuit 10 of 83. It is also possible, however, first to cause the electrons to impinge on the nets 66 and 66' and, in the known manner according to Weiss, liberate at these nets secondary electrons in comparatively large number. If this is done, there is 15 ultimately obtained at the final anode 17 a considerably amplified effect of the ikonoscope.

This final effect has the advantage that it becomes zero in the case of black points of the image. There is no feed current which might 20 produce any interfering shot noise, since the primary cathode, viz., the contents of the meshes 7c, consists of insulated particles which continue to discharge until no further electrons can be emitted.

25 In the practical embodiment there are naturally several other practical points which require to be considered:

1. The illuminating light 84 should liberate electrons not from the nets 83, 66, 66' but only 30 from the mosaic 7c. Since the anticathodes 66, 66' etc., also consist of silver and caesium, the light is to be so guided that it does not meet against the meshes, i. e., enters obliquely. By the way, the emission of subsequent anticathodes is not dangerous, as it is not multiplied.

2. The sheet of mica 8 must cause an optical and an electrical separation of the two discharge spaces. It is made larger than the scanned area. In place of mica there may also be employed 40 black glass and the like.

In place of a laid-on net 83 a network which is applied by atomization may be employed with advantage.

For the sake of clear comprehension Fig. 13 45 shows a plan view of the rear mosaic 7c consisting of insulated particles, which are photo-electrically activated and of the net 83 which is preferably made of a noble metal, gold, platinum and the like, so that it will not emit electrons by itself.

We claim:

1. A television system for translating an optical image into one electrical representation thereof comprising a substantially planar mosaic 55 formed of a multiplicity of electrically isolated individual elements, a foraminous grid electrode element positioned in a plane parallel to the mosaic and relatively adjacent thereto, the opposed surfaces only of both the mosaic and the grid element being light responsive, optical means for projecting and focusing an optical image through

the mosaic onto the light responsive surface of the grid element to release therefrom electrons and to produce thereby an electronic current replica of the optical image, means including a source of high frequency for producing an alternating high frequency electrostatic field between the mosaic and the grid element for directing the electronic current replica onto the mosaic to produce a substantially complete electrostatic image thereof over the surface of the mosaic, a beam of light of substantially elemental cross-sectional area, means to scan the light responsive surface of the mosaic according to a pre-established scanning pattern by directing the beam of light through the foraminous grid element to liberate, as a result of scanning, electrons from the individual elements of the mosaic, the number of electrons liberated being proportionally related to the variance of the electrostatic charge image produced on the individual elements of the mosaic, and means to collect the liberated electrons.

2. A television system for translating an optical image into one electrical representation thereof comprising a substantially planar mosaic formed of a multiplicity of electrically isolated individual elements, a foraminous grid electrode element positioned in a plane parallel to the mosaic and relatively adjacent thereto, the opposed surfaces only of both the mosaic and the grid element being light responsive, optical means for projecting and focusing an optical image through the mosaic onto the light responsive surface of the grid element to release therefrom electrons and to produce thereby an electronic current replica of the optical image, means including a source of high frequency for producing an alternating high frequency electrostatic field between the mosaic and the grid element for directing the electronic current replica onto the mosaic during each half cycle of a predetermined polarity, to produce a substantially complete electrostatic image thereof over the surface of the mosaic, a beam of light of substantially elemental cross-sectional area, means to scan the light responsive surface of the mosaic according to a pre-established scanning pattern by directing the beam of light through the foraminous grid element to liberate, as a result of scanning, electrons from the individual elements of the mosaic, the number of electrons liberated being proportionally related to the variance of the electrostatic charge image produced on the individual elements of the mosaic, the liberated electrons being directed through the grid element during each half cycle of the opposite polarity, means to collect the liberated electrons, and a load circuit for utilizing the collected electrons.
